UNITED STATES PATENT OFFICE.

HARRY ZIMMERMAN, OF FREMONT, OHIO.

SHUTTER-FASTENER.

No. 839,693.

Specification of Letters Patent.

Patented Dec. 25, 1906.

Application filed February 15, 1906. Serial No. 301,257.

To all whom it may concern:

Be it known that I, HARRY ZIMMERMAN, a citizen of the United States, residing at Fremont, in the county of Sandusky and State of Ohio, have invented certain new and useful Improvements in Shutter-Fasteners, of which the following is a specification.

My invention relates to shutter-bowers, and more especially to that class of shutter-bowers indicated in Letters Patent No. 445,210, and has for its object to overcome certain defects in the construction shown in such devices, to which end I have devised the improvements hereinafter set forth and as illustrated in the accompanying drawings, in which—

Figure 1 is a perspective view of a shutter and frame and bower to illustrate my improvements. Fig. 2 is a longitudinal section 20 of the sill-plate; Fig. 3, a transverse section of the sill-plate and catch device; Fig. 4, a transverse section on the line 4-4, Fig. 1; Fig. 5, a longitudinal section illustrating one feature of my invention. Fig. 6 is a view showing part of a retaining-rod with a different form of enlargement from that shown in other figures.

The device is adapted for use in connection with the sill A and pivoted shutter B, to 30 which is connected a retaining rod or bar D, as usual, the said rod having at the end a finger a. In connection with these parts there is an improved sill-plate E, which has a series of sockets e, in line with each other, and 35 terminal-sockets f, arranged side by side upon opposite sides of the central line of the plate and preferably elongated. This arrangement of the two series of sockets I do not here claim, as it is the subject of an application, Serial No. 295,924, filed January 13, 1906.

The sill-plate E is secured to the sill A in any suitable manner. Preferably two of the 45 sockets e have countersunk holes in the bottom thereof to receive the heads of screws which pass into the sill-plate.

In this class of devices as heretofore constructed, the finger at the end of the retaining-rod D engages the sockets, and there is a 50 tendency, especially if the finger gets slightly bent, for the same to jump out of the socket in which it is placed in case of any pressure upon the shutter tending to vibrate the same, as from gusts of wind and otherwise. I have

obviated this objection by contracting the 55 sockets toward the upper ends, as shown in Fig. 5, and providing the rod D with an enlargement d, so as to form a beveled or tapering face c, the greater diameter of the enlargement not exceeding that of the contracted mouth of the socket. As a result of this construction if the finger is in the end of a socket, as shown in Fig. 5, any draft or thrust upon the rod D will bring the beveled face of the finger against the beveled or inclined side of the socket, whereby the action will tend to draw the finger downward, so that it is practically impossible for it to escape unless the rod is moved directly upward. While the construction shown in Fig. 70 5, where the sockets are contracted at their upper ends, will secure this result, the finger would fit loosely in the socket when in place and there would be an opportunity for it to play and allow the shutter to play and rattle. 75 I therefore prefer to contract each socket both at the top and bottom, as shown in the other figures, and to taper the end of the finger as well as provide the tapering face c, so that when the finger rests in its socket, as 80 shown in dotted lines, Fig. 2, it will have a close bearing against the sides thereof and rattling is prevented.

The enlargement may be made in different ways, either as shown in Fig. 5 or in Fig. 3 85 and in dotted lines, Fig. 2, or it may be spherical, as in Fig. 6.

There is sometimes a tendency on the part of the catch to lift from engagement with the sill-plate when constructed as usual, and to 90 avoid this I construct the catch device with the usual plate g, with an opening for the passage of the finger of the retaining-rod and with a finger h to engage one of the sockets of the sill-plate and trunnions j, adapted to 95 sockets in the retaining-plate k. The trunnions j, however, instead of being in line with the plate g are arranged upon a plane below the plane of the bottom of said plate, as in Fig. 3, so that in swinging about its trunnions the tendency of the plate is to carry 100 the finger h into better engagement with the side of the socket and reduce its tendency to jump out of the socket.

It will be seen that in case a sill-plate I, 105 having a single socket, is used for holding the shutter open this socket may be constructed in the same manner as those of the other sill-

plate. It will further be seen that the sill-plate with sockets constructed toward the top may be used to advantage with the ordinary hooked retaining-rod, especially if the hook is slightly bent inward.

I do not here claim the construction of catch device herein shown, as it constitutes the subject of a separate application for Letters Patent, Serial No. 326,746, filed July 18, 1906.

Without limiting myself to the precise constructions shown, I claim—

1. The combination in a shutter-bower, of a sill-plate provided with a socket to receive the end of a securing-rod, the said socket contracted toward the top, and a pivoted securing-rod enlarged at the end.

2. A sill-plate for a shutter-bower provided with a socket to receive the end of a securing-rod, said socket contracted toward both the top and bottom.

3. A sill-plate for a shutter-bower provided with a series of sockets in line with each other and contracted toward the top, and with a plurality of sockets at the end of the plate on opposite sides of the center thereof and also contracted at the top.

In testimony whereof I affix my signature in presence of two witnesses.

HARRY ZIMMERMAN.
